(57) **CLAIM**

The ornamental design for a combined weed cutting and removal apparatus, as shown and described.

DESCRIPTION

FIG. 1 is a front, top perspective view of the combined weed cutting and removal apparatus;

FIG. 2 is a top plan view of the combined weed cutting and removal apparatus;

FIG. 3 is a bottom plan view of the combined weed cutting and removal apparatus;

FIG. 4 is a left-side elevation view of the combined weed cutting and removal apparatus;

FIG. 5 is a right-side elevation view of the combined weed cutting and removal apparatus;

FIG. 6 is a front elevation view of the combined weed cutting and removal apparatus;

FIG. 7 is a rear elevation view of the combined weed cutting and removal apparatus; and,

FIG. 8 is perspective view of the combined weed cutting and removal apparatus coupled to a pitchfork.

The pitchfork shown in broken lines in FIG. 8 is for the purpose of illustrating environmental matter that forms no part of the claimed design, and the remaining broken lines in FIGS. 1-8 illustrate portions of the combined weed cutting and removal apparatus that form no part of the claimed design.
